UNITED STATES PATENT OFFICE.

HANS. T. JOHNSON, OF CHICAGO, ILLINOIS, ASSIGNOR TO OLE BERG, OF SAME PLACE.

DESIGN FOR A PICTURE-FRAME.

SPECIFICATION forming part of Design No. 21,078, dated September 29, 1891.

Application filed August 24, 1891. Serial No. 403,631. Term of patent 7 years.

To all whom it may concern:

Be it known that I, HANS. T. JOHNSON, a citizen of the United States, residing at Chicago, in the county of Cook and State of Illinois, have invented and produced a new and original Design for Picture-Frames, of which the following is a specification, reference being had to the accompanying illustration, forming a part thereof.

10 The illustration is a photograph of a picture-frame in front elevation embodying my design.

15 My invention relates more particularly to frames which are enameled, and the leading feature of my design is a sinuous or scalloped contour of both the sides and ends of the frame on both the inner and outer edges thereof.

20 In the illustration, a picture-frame A is represented, a being the sides thereof, and a' the ends. These parts of the frame are all made with sinuous outlines, both on the inner and outer edge thereof, as clearly shown in the illustration, the curves alternating 25 with each other on opposite edges, so as to give to the entire piece a wavy appearance. The illustration shows a frame to which the

enamel has also been applied, and this covering is lined or ribbed, the lines a^2 being made to follow the curvatures of the frame-body. 30

In the illustration the four outside corners a^3 of the frame are shown as brought out square—that is, so that the outline thereof will be a right angle. This particular form of the corners I prefer; but I also carry out 35 my design with round corners, the outer configuration thereof corresponding to the inner curvature, the same as in other parts of the frame. Either corner may be used with my design, the characteristic of which is the 40 formation of the sides and ends of the frame with sinuous or wave-like bends or curves in the entire body of these parts, so that both the inner and outer edges will present a sinuous or wavy outline. 45

Having thus described my invention, what I claim as new, and desire to secure by Letters Patent, is—

The design for a picture-frame, substantially as herein shown and described.

HANS T. JOHNSON.
